ROTARY PHOTOGRAVURE PRINTING APPARATUS

Angus Murray Halley, Moseley, Birmingham, England

Application June 29, 1950, Serial No. 171,152
In Great Britain May 8, 1950

5. Claims. (Cl. 101—169)

1 This invention has reference to improvements connected with rotary photogravure printing apparatus and relates particularly to an improved means for reciprocating the doctor blade thereof relative to the image cylinder.

The object of the present invention is to provide a means as aforesaid wherein a constant smooth reciprocation of the doctor blade is ensured for all positions or settings of the doctor blade housing as provided for in the description of my co-pending application No. 171,151 of even date.

The invention consists of a rotary photogravure printing apparatus incorporating means for reciprocating a doctor blade relative to an image cylinder comprising a pair of driven pinions possessing a different number of teeth each meshing with one of a pair of pinions freely rotatable about a spindle to be reciprocated, one of said last mentioned pinions being restrained from axial movement relative to the reciprocal shaft and being integral with or connected to a sleeve in which is formed an endless circumferential cam track engaged by a pin or roller carried by the other pinion about the reciprocal shaft which last mentioned pinion is restrained from axial movement.

The invention will now be described with particular reference to the accompanying drawing which shows a longitudinal sectional view of the means for reciprocating the doctor blade housing. The printing apparatus is desirably of the kind described in my co-pending application No. 171,151 of even date wherein there is provided a quasi-cylindrical housing 1 for a doctor blade (not shown) which housing is mounted in end plates 2 capable of being rocked about the longitudinal axis of a cylindrical sealing member 3. In operation it is desirable that the doctor blade should be reciprocated longitudinally relative to the image cylinder with which it is adapted to have peripheral contact and to this end, according to the present invention, the doctor blade housing 1 is axially reciprocated by the following means.

Rotatably mounted on a stub axle 4 in axial prolongation of the longitudinal axis of the cylindrical sealing member 3 are a pair of pinions 5 and 6, the pinion 5 having one tooth more than the other pinion 6. Desirably these two pinions 5 and 6 are mounted on or formed integral with a common sleeve 7 and the pinion 6 is of greater axial length than the pinion 5 for a reason which will become apparent from the later description. The pinion 6 is in mesh with

2 a pinion 8 formed in a sleeve 9 having antifriction mounting 10 about a trunnion 11 on the one end of the doctor blade housing 1, this sleeve 9 being prevented from axial movement relative to the trunnion 11 by means of key rings 12 and shoulders 13 on the trunnion against which the end of the one anti-friction mounting 10 abuts. The pinion 5 is in mesh with a pinion 14 formed on a sleeve 15 having an annular groove 16 engaged by a key 17 secured to the end plate 2 by a pin 18. Thus since the end plates are restrained from axial movement on the stub axle 4 fixed to the frame 19 of the machine the sleeve 15 is restrained from any axial movement. The sleeve 15 carries a radial and inwardly directed pin 20 carrying a roller 21 engaging in a peripheral endless cam track 22 in the sleeve 9.

In operation it will be appreciated that when the pinions 5 and 6 are rotated by any convenient means then by virtue of the different number of teeth on their peripheries, the pinions 14 and 8 and therefore the sleeves 15 and 9 are rotated at slightly different speeds and since the sleeve 15 cannot move axially the sleeve 9 is caused to move axially together with the doctor blade housing 1 by the movement of the roller in the cam track 22 thereby imparting a slow constant longitudinal reciprocation to the doctor blade. The fact that the pinion 6 is of substantial axial width ensures that the driving engagement between the pinions 6 and 8 is maintained during the reciprocation of the doctor blade housing. It will be appreciated that this construction admits of a constant reciprocation of the doctor blade housing 1 for all settings of the end plates 2 about the axis of the stub axle 4.

What I claim is:

1. In a rotary photogravure printing apparatus means for reciprocating a doctor blade housing comprising in combination, an extension of the doctor blade housing, a first pinion freely rotatable about said extension but restrained from axial movement relative thereto, a second pinion freely rotatable about said extension but restrained from axial movement relative to the apparatus, a pair of positively driven pinions rotatable about a common axis and each meshing with one of said first and second pinions, the gear ratio between said first pinion and the positively driven pinion meshing therewith being different from the gear ratio between the second pinion and the positively driven pinion meshing with said second pinion, and a cam engagement

between said first and second pinions for converting relative rotation between said first and second pinions into a reciprocal motion of the doctor blade housing.

2. In a rotary photogravure printing apparatus means for reciprocating a doctor blade housing comprising in combination, an extension of the doctor blade housing, a first sleeve rotatable about said extension and restrained from axial movement thereon, a pinion on said first sleeve, a second sleeve rotatable about the first sleeve and restrained from axial movement relative to the apparatus, a pinion on said second sleeve, a cam track in one of said sleeves, a roller on the other of said sleeves engaged in the cam track for converting relative rotation between the two sleeves into an axial movement of the first sleeve and a pair of positively driven pinions mounted upon a common axis, one of said last pinions meshing with the pinion in the first sleeve with a particular gear ratio and the other meshing with the pinion in the second sleeve with a gear ratio different from the particular gear ratio.

3. In a rotary photogravure printing apparatus means for reciprocating a doctor blade housing comprising in combination, an extension of the doctor blade housing, a first sleeve rotatable about said extension formed with a peripheral cam track therein and restrained from axial movement relative to the said extension, a second sleeve rotatable about said first sleeve and restrained from axial movement relative to the apparatus, an inwardly directed pin in said second sleeve engaging the cam track in said first sleeve for converting relative rotation between the first and second sleeves into a reciprocal motion of the first sleeve, pinions on each of said sleeves, and a pair of driving pinions mounted for rotation about a common axis, said driving pinions meshing with said sleeve pinions

one at one gear ratio and the other at a different gear ratio.

4. In a rotary photogravure printing apparatus means for reciprocating a doctor blade housing according to claim 3, comprising also a roller around the pin on the second sleeve engaging the cam track in the first sleeve.

5. In a rotary photogravure printing apparatus means for reciprocating a doctor blade housing comprising in combination, sideplates rockable about a fixed axis, trunnions on the doctor blade housing mounted in said side plates, a first sleeve rotatable about one of said trunnions having a peripheral cam track and an integral pinion and being restrained from axial movement on the trunnion, a second sleeve with integral pinion mounted about the first sleeve and having an annular groove, a key fixed to the adjacent side plate and engaged in said annular groove, an inwardly directed pin on said second sleeve, a roller about said pin engaging the cam track in the first sleeve and a pair of driven pinions mounted for rotation about an axis coincident with the fixed axis about which the side plates may be rocked each in mesh one at one gear ratio and the other at a different gear ratio with one of the pinions on the first and second sleeves.
